MEANS FOR ACIDIZING GAS WELLS

Elbert S. Villines, Lakin, Kans.

Application August 8, 1947, Serial No. 767,409

1 Claim. (Cl. 166—1)

1

2

This invention relates to an improved apparatus for acidizing gas wells.

It is an object of this invention to provide apparatus for an improved procedure for acidizing gas or oil wells in which a swab-packer on a flexible support is introduced into a well, an acidizing solution is introduced through perforations in the casing above the swab packer and the swab packer is then removed.

A broad embodiment of my invention comprises introducing an acidizing tool by means of a letting-in tool and cable into a gas well, disengaging and withdrawing said letting-in tool, shutting in said well, introducing acid through casing perforations above said acidizing tool, and then removing said acidizing tool.

In acidizing gas well formations to increase the flow of natural gas, it is sometimes necessary to introduce dilute hydrochloric acid solution through perforations in the well casing to reach the gas producing horizons. This is especially true where the well is cased to the bottom, or through the gas producing horizon, and then gun perforated opposite the gas bearing strata. The usual practice is to run a bridge plug to a point below the perforations, set the plug, acidize, and then go in with tools and drill out the bridge plug which is a time consuming and expensive operation. Another means often employed is to run a packer on a tubing string and setting said packer below the perforations through which it is desired to treat the gas producing formation by introducing a dilute hydrochloric acid solution. Running packers on tubing is also expensive and time consuming. A more desirable method and means to accomplish the above and reduce the time and expense factors is to use a combination swab-packer-tool that will presently be described in light of the accompanying drawings.

Figure 1 is a vertical sectional view showing the selective acidizing tool being run into a gas well.

Figure 2 is an enlarged vertical sectional view showing the parts of the acidizing tool in detail and their relation to each other.

Figure 3 is a fragmentary view partly in section and partly in side elevation showing the connection between the letting-in tool and the tool body.

Figure 4 is a cross-section of Figure 3 taken along the line 4—4.

Figure 5 shows the tool set in position in the well bore, and the well closed in and filled with fluid.

Figure 6 shows the tool being withdrawn from the well.

Figure 7 shows a detail of the fishing tool or overshot.

Referring to Figure 1, a suitable reel 1 which is mounted on, and part of a regular well servicing unit, has wound thereon a sand line 2, passing over a sheave 3, suspended suitably above the well bore. Valves 4 and 5 are connected to the casing 6. With valve 4 and its supporting member easily detachable from casing 6, and of split construction of the type well known in this art, the tool may easily be introduced into the casing 6. On the end of line 2, a rope socket 7 is firmly secured into which is screwed the letting-in tool 8, which is coupled to the selective acidizing tool comprising parts 9 through 24 inclusive, and shown in detail in Figure 2.

Referring to Figure 2, any fluid in the hole such as gas, water, spent acid solution, or petroleum or its fractions will offer considerable resistance to flow past the cups 19. Therefore these fluids are directed through the perforations 23' in the length of tubing 23, and caused to flow upward through the tool to ball valve 15 which is raised from seat 16 and the fluid passes through perforations 14 in cage 13 to emerge above cups 19. When the tool reaches bottom, it is raised slightly and dropped. The weight of rope socket 7 plus letting-in tool 8 and any other tools, such as jars and stem, is sufficient to bend pin 10 into grooves 11 so that rope socket 7 and letting-in tool 8 may be withdrawn from serrated sub 12, of the selective acidizing tool, as shown in Figures 3 and 4.

Still referring to Figure 2, it is to be seen that letting-in tool 8 has a hole drilled near the bottom to match a similar hole in sub 12; the hole in tool 8, however, does not go all the way through the body of 8. Pin 10 is of soft material and is held in place by pin 9 which fits in a hole drilled at right angles through the lower portion of 8 such that it intersects the hole for pin 10 on the center line to hold pin 10 in position.

In Figures 3 and 4, after the entire assembly has been dropped, the weight of socket 7 and letting-in tool 8 and jars and stem bends the ends of 10 down into the milled grooves 11, thus disengaging the letting-in tool 8 from the sub 12, and leaving the selective acidizing tool in the hole. Rope socket 7, and letting-in tool 8 and jars and stem are now withdrawn from the well bore as shown in Figure 5. The principle parts of the selective acidizing tool are (refer to Figure 2) 55 serrated sub 12, which is securely joined to cage

13, with perforations 14, ball 15 and seat 16. A mandrel tube 17 is screwed into the bottom of 13 and spacer tube 18 fixes the position of the packer cup 19, which is of rubber or similar suitable material and its reinforcing metal cup 20. As many of these cup combinations may be spaced on mandrel 17 as desired by using a suitable number of spacers 18, all locked securely by collar 21. The tubing anchor, comprised of collar 21, tubes 22, 23 and bull plug 24, is made of such length that the packer will seal off the bottom of the well from the perforations 25 which are opposite the gas zone.

In Figure 5 the selective-acidizing tool is set in a well bore below the perforations 25. Valve 4 is closed and one valve 5 is closed which is connected to the line running to the mud pit, or blow down pipe. The other valve 5 is connected to a pump (not shown) and acid solution is introduced in the well bore when the cups 19 seal the upper portion of the well from the lower portion such that the acid is forced into the gas strata through perforations 25. The acid is followed by a water flush in sufficient quantity to clear the casing of the acid solution. A part of this water is now swabbed from the hole, and the selective acidizing tool is retrieved as follows:

A fishing tool 26 is attached to rope socket 7, see Figure 7. The fishing tool shown is well known in the art. The angular mouth 28 guides the body 26 over serrated sub 12 such that slips 27 engage sub 12, the internal surface 29 of body 8 is inclined at an angle and so proportioned that slips 27 move out horizontally as they are moved upward. As the overshot or fishing tool takes hold the slips engage the serrations on sub 12, thus firmly securing the selective acidizing tool to the fishing tool 26. The proportions of 26 and 27 are such that the slips 27 cannot fall out of the beveled mouth 28, before engaging sub 12.

As the tool is removed from the well, see Figure 6, the swabbing action of the cups 19 remove the excess fluid above the tool and lower the pressure across the perforations 25 so the spent acid solutions tend to flow into the well bore, thus cleaning the newly created porosity and permeability developed by the acid treatment.

Other modifications may be made within the scope of the following claim:

I claim as my invention:

Apparatus for acidizing gas wells comprising

a tool body having an upwardly facing packet cup on its outer surface for sealing engagement with the wall of a well bore upon existence of pressure above said packer cup greater than the pressure below such cup, a longitudinal passage through said body, a tubing anchor depending from said body for supporting said body above the bottom of a well, perforations above and below said packer cup communicating with said passage to permit flow of gas upwardly through said passage from below said packer cup during lowering of said apparatus into a gas well, a one-way valve in said passage preventing flow of fluid downwardly through said passage, a cable for lowering said body into a gas well, releasable means for connecting said cable to said body, said means comprising an upwardly extending member on said body having a transverse opening therethrough, the outer ends of said transverse opening terminating in vertical grooves in the side walls of said upwardly extending member, said grooves extending downwardly from said ends of said opening, a letting-in tool secured to said cable, said letting-in tool having a central cavity therein for reception of said upwardly extending member, and a bendable pin extending through said opening in said upwardly extending member and having its outer ends extending into the side walls of said cavity to support said body member from said letting-in tool, said bendable pin being capable of having its outer ends bent downwardly into said grooves and out of holding engagement with the side walls of said cavity upon dropping said body and letting-in tool a short distance to cause said tubing anchor to strike the bottom of a well.
